UNITED STATES PATENT OFFICE.

GRIGORI PETROFF, OF PETROGRAD, RUSSIA, ASSIGNOR TO AKTIONS COMPANY
"KONTAKT," OF PETROGRAD, RUSSIA.

PRODUCT AND PROCESS OF MANUFACTURING A PRODUCT HAVING THE PROPERTIES OF SOAP.

1,196,274.

Specification of Letters Patent. Patented Aug. 29, 1916.

No Drawing.

Application filed July 25, 1913. Serial No. 781,170.

To all whom it may concern:

Be it known that I, GRIGORI PETROFF, a subject of the Czar of Russia, residing at 23 Pesotchnaia ulitsa, Petrograd, Russia, have 5 invented certain new and useful Improvements in the Product and Process of Manufacturing a Product Having the Properties of Soap, of which the following is a specification.

10 This invention relates to an improved product and process for the production of detergents and detergent emulsions.

Animal or vegetable fats and oils have been hitherto chiefly used as raw material 15 for the manufacture of soap. Sometimes naphthenic acids or resin, or colophony have been partly used for the same purpose. I have now found that sulfur containing compounds produced by treating mineral oil

20 hydrocarbons, crude petroleum, its heavy lubricating distillates, lubricating mineral oils and the like with sulfuric acid and separating with the aid of suitable solvents, for example, ethyl or methyl alcohol or acetone

25 from the unattacked hydrocarbon, the material formed by the action of the sulfuric acid upon the constituents of the hydrocarbon mixture treated and which materials are herein referred to as sulfonic acids obtained 30 from sulfonated mineral oils, may also be employed as raw material for producing a detergent which, similar to ordinary soap made of fats and oils, is well adapted for washing purposes and for re-

35 placing ordinary soap in many branches of industry and in the household. Such a soap substitute has nothing in common with so-called naphtha soaps which consist exclusively of salts of naphthenic acids. Further

40 the new soap substitute has the substantial advantage over naphtha soap, in that it does not possess the obnoxious odor frequently associated with such soaps. In regard to detergent capacity it is in no way inferior

45 to good brands of soaps made from fat. For the preparation of a detergent, the said sulfonic acids are mixed in aqueous or alcoholic aqueous solution in the cold or with warming with carbonic or caustic alkalis or

50 ammonia. According to the conditions, neutral acid or alkaline solutions of salts of the sulfonic acids are obtained, from which neutral, acid or alkaline solutions, the greater part of the solvent may be re-

55 moved by means of a current of air, or the solution of salts may be boiled until the desired degree of concentration is attained. According to the particular treatment employed, a hard or semi-liquid gelatinous substance is obtained, comparable to hard or 60 soft soap. The sulfonic acids used as raw material may be employed either in a pure state or mixed with fats, fatty oils and fatty acids.

In contradistinction to ordinary soap, the 65 product manufactured in accordance with the improved process from sulfonic acids does not form any deposit with lime or magnesium salts and therefore lathers well even when used with sea water or hard water. 70

The inventor has further established that the washing capacity is not restricted to the alkali salts of the sulfonic acids alone, but that said capacity is being possessed by the sulfonic acids themselves in their pure 75 state. Soaps, prepared from such sulfonic acids possess advantages as compared with ordinary soap or with soaps prepared from naphthenic acids or from sulfonated fatty oils, for instance from sulfo-castor-oil acids 80 (Turkey red oil). The main advantage of sulfo-acid soap is that it can be used both either in acid solutions or in alkali and neutral solutions. Their alkali salts in aqueous solutions do not undergo the character 85 of hydrolytic decomposition such as takes place with ordinary soaps, hence the sulfonic acid soaps remain neutral while ordinary soaps have an alkaline reaction.

The sulfonic acid soaps formed as described dissolve in hard waters without 90 forming deposits, and this water soluble characteristic of the product renders it available for many commercial uses other than detergent, its soap-like properties, however, afford 95 an identifying basis enabling the distinct new product to be definitely defined.

To enable others to definitely carry on this process and produce the product, the following directions will suffice, although I do 100 not thereby desire to be limited to the relative proportions indicated. The sulfonic acid formed by sulfonating mineral oils, from which the sludge has been removed, is apt to be mixed with or to some extent dissolved in unattacked portions of the mineral oil. This mineral oil sulfonic acid material is mixed with an alkali and a solvent in 105

which the sulfonic acid or its alkali compound is readily soluble, and in which any unattacked portions of the mineral oil is relatively insoluble. The result is that the sulfonic acid combines with the alkali in a non-oily solution, and the solvent being volatile, can readily be driven off by heat or distillation, producing a substantially oil free alkaline sulfonated mineral oil product.

For producing a neutral product, a fourteen (14) to sixteen (16) per cent. solution of about 11.4 kilograms of caustic potash or soda, or carbonate of ammonium, is mixed with, say 100 kilograms of aqueous alcohol solution of the sulfonic acid, the solution containing approximately say fifty (50) per cent. of sulfonic acid. The amount of alkali can be increased or decreased, approximately at, or on either side of the neutral, depending upon whether a slightly alkaline, acid, or neutral product is desired. Any excess oil present with the sulfonic material treated will not go into the aqueous solution with the sulfonic material, and so the solution can be separated from undissolved oil, and the neutral sulfonic product can be separated very easily, by volatilizing off the solvent. In this way I produce a very pure, substantially oil free, alkali sulfonic product from mineral oils, having distinctly new properties and valuable commercial uses.

Having described my invention, I claim:

1. A process for producing a sulfonic ma-

terial having soap-like properties, which consists in mixing sulfonic acids formed by sulfonating mineral oils with an alkali and a solvent in which the sulfonic-alkali compound is readily soluble and in which unattacked portions of the mineral oil are relatively insoluble, and separating the said compound from its solvent.

2. In a process for producing a material having soap-like properties, the steps comprising treating with an alkali and an aqueous alcohol solution, sulfonic acids formed by sulfonating mineral oils.

3. A sulfonated mineral oil sulfonic-alkali compound having soap-like properties characterized by solubility in hard water without forming a deposit.

4. A soap-like product consisting of an alkali compound of sulfonic acid formed by sulfonating mineral oils, substantially oil free, neutral and water soluble without forming deposits.

5. A material consisting of an alkaline compound of sulfonic acid formed by sulfonating mineral oil and characterized by having soap-like properties without undergoing hydrolytic decomposition in water solution.

In testimony whereof I affix my signature in presence of two witnesses.

GRIGORI PETROFF.
